MULTIPOLE ELECTRIC SWITCH

Hugh W. Batcheller, Newton Highlands, Mass., assignor, by mesne assignments, to Ark-Les Switch Corporation, Watertown, Mass., a corporation of Massachusetts

Application November 30, 1946, Serial No. 713,233

1 Claim. (Cl. 200—6)

1

This invention relates to a multi-pole electric switch adapted for use with electric ranges and for similar purposes where it is necessary or desirable to connect together various electrical elements in different combinations. In using electric ranges, it is desirable to have a considerable number of different degrees of heating, ranging from a very low heat to the highest heat to be had from the heating unit employed. For this purpose it is desirable to connect a range or the like to a three-wire circuit so that two different voltages are available. By connecting the heating unit in various combinations with two resistance units of different magnitudes, seven different degrees of heating can be obtained. It is an object of the present invention to provide a switch which is adapted to connect such resistance units and the heating unit to a three-wire circuit in different combinations so as to give seven different degrees of heating as desired, the switch being compact in structure, easy to assemble and consisting of a minimum number of parts. To this end, the switch hereinafter described is characterized by a rotor which has a series of annular faces against which a number of arms are resiliently pressed, each arm having a boss thereupon which is adapted to move into and out of recesses in the annular faces so as to spring the respective arms away from contact with the annular faces and thus to make or break contact between contact elements on the end portions of such arms and fixed contact elements engageable thereby.

In order to make the connections for which the switch is designed, six such arms are required. According to the invention, these arms are arranged in pairs in parallel planes, and the annular faces of rotor on which the arms bear are likewise in parallel planes. This makes for compactness of structure. In order to facilitate assembling of the part which go into the casing, the rotor is preferably made so that its annular faces are of different diameters, this resulting in a stepped or terraced structure as illustrated.

For a more complete understanding of the invention, reference may be had to the following description thereof and to the drawings, of which:

Figure 1 is a front elevational view of a switch embodying the invention;

Figure 2 is a rear elevational view of the same;

Figure 3 is a section taken on the line 3—3 of Figure 1;

Figure 4 is a section on the line 4—4 of Figure 1;

2

Figure 5 is a section on the line 5—5 of Figure 3;

Figure 6 is a section on the line 6—6 of Figure 3;

5 Figure 7 is a section on the line 7—7 of Figure 3;

Figure 8 is an isometric view of the rotor;

Figure 9 is an isometric view of the various conductors within the switch, shown in their 10 relative positions;

Figure 10 is a face view of the rotor;

Figure 11 is a section on the line 11—11 of Figure 4.

The switch comprises a casing 20 preferably 15 of insulating material which encloses the working parts of the switch and acts as a support for the several conductors contained therein. These conductors, as hereinafter described, are conveniently secured to the casing 20 by rivets which extend through the wall of the casing. In molding the casing, it is economical to mold the holes through which the rivets are to extend. The casing is designed so that all such holes are through the rear wall thereof. In this way all 20 of the rivet holes can be formed in the molding operation. A cover plate 22 is adapted to be secured to the open front of the casing 20 to act as a closure therefor.

As indicated in Figure 4, a rotor 24 which is 30 preferably of insulating material and which is mounted on and keyed to a shaft 26 is journaled in the casing 20 as at 28, the shaft 26 also bearing in an opening in the front cover plate 22. A suitable finger knob 30 is mounted on the forward 35 end portion of the shaft 26 to facilitate manual rotation of the shaft 26 and the rotor 24 which is mounted thereon.

In order to hold the rotor yieldingly in any 40 one of eight angular positions, one or more detents are provided, such detents being preferably in the form of small balls 32 which are pressed by springs 34 housed in bores extending into the front face of the rotor 24 near the shaft 26. The balls 32 are pressed by the springs into 45 shallow recesses 36 (Figure 11) in the rear face of the cover plate 22. Thus the rotor is yieldingly held in any one of eight angular positions equally spaced by angles of $22\frac{1}{2}^\circ$. The rotor 24 is illustrated in Figures 8 and 10 and is characterized by 50 three annular faces 38, 40 and 42 which are in parallel planes perpendicular to the axis of rotation of the rotor and which are preferably of different diameters, the face 38 having the largest diameter. This results in a stepped or terraced 55 formation on the rear end of the rotor. The cas-

ing 20 serves as a support for a number of conducting parts, such as are illustrated in Figure 9 and several of the other figures. These conductors include two U-shaped conductors 44 and 46 which are mounted on the support 20 in parallel planes which are substantially the planes of the annular faces 38 and 40. The conductor 44 is the larger of the two U-shaped conductors and includes a pair of arms 48 and 50, the ends of which are free, these ends having contact elements 52 and 54 which are pressed by the resilience of the arms against fixed contact elements 56 and 58, respectively, the fixed elements being mounted on the support 20 and being electrically connected respectively to external terminals 60 and 62. The arms 48 and 50 of the U-shaped conductor 44 extend across spaced portions of the annular face 38 of the rotor 24, the rotor being disposed between these arms when it is mounted for rotation within the casing. The arm 48 is provided with a raised element or boss 64 which projects from the front face of this arm and bears on the annular face 38 of the rotor 24. Similarly, the arm 50 is provided with a boss 66 which projects from its front face and bears on the face 38. As indicated in Figure 9, the boss 64 is at a greater radial distance from the axis of the rotor than is the boss 66. Hence, as the rotor rotates, the bosses 64 and 66 describe different concentric paths on the annular face 38, the boss 64 describing an outer path and the boss 66 describing an inner path. As shown in Figures 8 and 10, an arcuate recess or depression 68 is provided in the outer path on the face 38, and two recesses 70 and 72 are provided in the inner path. The relative arrangement of the face 38, the bosses 64 and 66 and the contact elements 52, 54, 56 and 58 is such that when the boss 64 is in the depression 68, the contact elements 52 and 56 are pressed together, but when the boss 64 is bearing on the normal surface of the face 38, the contact element 52 is held away from the element 56. In like manner, the contact elements 54 and 58 are pressed together only when the boss 66 is in the recess 70 or 72. Thus the lengths and angular positions of the recesses determine whether the contact elements are engaged or disengaged for the various angular positions of the rotor 24.

The small U-shaped conductor 46 is somewhat similar in shape to the larger conductor 44 and includes a pair of arms 74 and 76 which extend over diametrically opposite portions of the annular face 40 on the rotor. The arms 74 and 76 are provided respectively with bosses 78 and 80 which follow outer and inner paths on the annular face 40 since they are at different radial distances from the axis of the rotor 24. As indicated in Figure 10, in the outer path on the face 40 are recesses 82, 84 and 86, the inner path having two recesses 88 and 90. These recesses determine the engagement or disengagement of corresponding contact elements 92, 94, 96 and 98, since the elements 92 and 96 are on the end portions of the arms 74 and 76, respectively, and the elements 94 and 98 are fixed and are connected electrically to the fixed elements 56, 58 respectively and hence to the terminals 60 and 62.

Instead of a third U-shaped conductor, two separate conductors 100 and 102 are mounted on the support 20 substantially in the plane of the annular face 42. The annular face 42 differs from the annular faces 38 and 40 by reason of the fact that most of it is recessed so that the face is at its normal level only at three points

104, 106 and 108, the remainder of the face being recessed. The conductors 100 and 102 are provided respectively with bosses 110 and 112 which are adapted to bear against the annular face 42 and to move in and out of the recesses which constitute most of this annular face. When the bosses 110 and 112 engage any of the elevated elements 104, 106 or 108, the corresponding conductor arm is swung away from the face 42 so as to disconnect a contact element 114 on the end of the arm 100 from contact with a fixed element 116 or to disconnect a contact element 118 on the end of the conductor arm 102 from the fixed element 116. Since most of the face 42 is recessed, it follows that the contact elements 114 and 118 are in contact with the fixed element 116 for most of the eight angular positions of the rotor 24.

The fixed contact element 116 is electrically connected to a terminal 120 on the back of the case 20. The U-shaped conductor 44 is electrically connected to a terminal 122. The U-shaped conductor 46 is connected to a terminal 124. The conductor 100 is connected to a terminal 126. The conductor 102 is connected to a terminal 128. These connections may be made by any suitable means. In the embodiment of the invention illustrated on the drawings, these connections are made by means of hollow rivets 130, 132, 134 and 136 which extend through suitable holes in the back wall of the casing, the interior of each rivet being screw-threaded to receive a binding screw which is inserted from the rear of the casing, the heads of these screws appearing in the rear elevational view of the casing shown in Figure 2. Some of these hollow rivets have hexagonal heads, as indicated in Figure 2, which are embedded in the casing to prevent the rivets from rotating when the screws therein are turned by means of a suitable tool. The contact elements 56 and 94 are parts of a single piece of sheet metal which is secured to the casing 20 and electrically connected to the terminal 60 by a pair of rivets 140. The contact elements 58 and 98 are parts of a single piece of metal which is secured to the casing 20 and the terminal 62 by a pair of rivets 142. All of these rivets extend through holes in the rear wall of the casing 20.

When the various terminals are properly connected to power lines and suitable resistances, suitable connections will result from turning the rotor to its various angular positions.

One embodiment of the invention herein shown and described is by way of illustration and not limitation, the invention being subject to such modifications and changes as may come within the scope of the appended claim:

I claim:

A multi-pole electric switch comprising a support, a rotor journaled in said support, said rotor having a stepped formation with three annular faces of different diameters, each of said faces having recesses therein, a U-shaped conductor of sheet spring metal mounted on said support substantially in the plane of the rotor face of largest diameter, the arms of said conductor traversing spaced portions of said face and having bosses resiliently bearing on said face at different radial distances from the axis of the rotor, said face having recesses adapted to receive said bosses when the rotor is revolved, a smaller U-shaped conductor of sheet spring metal mounted on said support substantially in

the plane of the annular face of medium diameter on the rotor, said smaller conductor having arms with bosses resiliently bearing on said medium diameter face at spaced points so that the bosses move into and out of recesses in said face when the rotor is revolved, fixed contact elements on said support engaged respectively by the end portions of the arms of both said U-shaped members when the corresponding bosses are within recesses, conductors mounted on said support 10 with bosses bearing resiliently against the annular face of smallest diameter to move into and out of recesses in said smallest face, and fixed contact elements engageable by the end portions of the last named conductors when the corresponding bosses are in recesses.

HUGH W. BATCHELLER.
